UNITED STATES PATENT OFFICE

CHARLES B. MACK, OF CHICAGO, ILLINOIS, ASSIGNOR, BY MESNE ASSIGNMENTS, TO CHERRY-BURRELL CORPORATION, OF CHICAGO, ILLINOIS, A CORPORATION OF ILLINOIS

VALVE DEVICE

Application filed December 22, 1924. Serial No. 757,391.

My invention relates to valve devices.

The object of the invention is to provide a simple, practical and efficient construction of balanced valve device.

5 In the accompanying drawings the figure is a view partly in elevation and partly in vertical section of a balanced valve device embodying my invention.

Referring to the drawings, 1 is a valve casting forming the body of the device, said casing 1 having an open end 2 and a side inlet or orifice 3. Within the casing 1 is a slideable hollow valve 4. The device is preferably mounted with the casing 1 vertically disposed, in which case the valve 4 will work up and down and the end opening 2 will be at the bottom of casing 1.

The valve 4 is made with open ends 5 and 6, whereof the open end 5 will be the top of the 10 valve and the end 6 the bottom of the same when the valve is arranged in vertical manner as referred to. In such case the valve will close the side opening 3 when in the 15 position shown in the drawings, which is its uppermost position, but when said valve is lowered its upper end passes below the top of side opening 3 and consequently liquid may flow between side opening 3 and orifice 2, thereby permitting passage of liquid through 20 the valve device. As valve 4 is lowered more and more it will open orifice 3 more and more and so open the valve device more and more until it is fully opened.

Casing 1 is provided with a shoulder 7, 25 which will be annular in case the casing 1 and valve 4 are annular, and this shoulder 7 limits the upward movement of valve 4 so that said valve will be checked or stopped when the valve device is closed.

40 The upper end of valve casing 1 is preferably made open and provided with a closing plug 9 by which it may be normally closed and this plug 9 is controlled and held in closing position by a rotary collar 10 having 45 projections 11 by which it may be turned, the upper end of valve casing 1 being threaded at 12 and collar 10 being interiorly threaded so that it may be screwed down on valve casing 1 to firmly clamp closing plug 9 in 50 position.

Plug 9 is preferably provided with a projecting tubular member 13 forming a stuffing box and containing packing material 14 and a packing gland 15 provided with apertures 16 by which it may be turned so as to 55 screw it down into tubular member 13.

A valve rod or stem 17 passes through stuffing gland 15, the same being preferably secured to valve 4 as by making said valve and rod 17 integral, and rod or stem 17 is 60 preferably made tubular and contains a float rod 18 which extends down through stem 17 and valve 4 and projects below the lower end of casing 1, and is provided with a float 20. A cotter pin 21 passes through members 17 and 65 18 so as to normally but detachably lock the same together, whereby valve 4 will be raised or lowered by raising or lowering rod 18, so that if float 20 is placed in a liquid containing vessel, and its position raised and lowered 70 by raising and lowering the level of liquid in said vessel, such operation will cause the raising and lowering of valve 4 and thereby open and close the same. Thus if desired the float 20 may be used and the valve device will 75 automatically control the valve so as to permit the valve to automatically regulate the liquid in the vessel, the valve being opened whenever the liquid level falls below a predetermined point.

Cotter pin 21 is preferably so located as to form a stop which will strike against the top of gland 15 and thereby limit the downward movement of the float and valve.

Inlet or orifice 3 may be connected in any 85 suitable way, one arrangement shown being to provide the same with a coupling member 23 controlled and held in position by a screw threaded collar 24, said member 23 having a threaded tubular socket 25, into which a 90 pipe or tubular member 26 may be fitted.

Thus it will be seen that the valve device provides a balanced valve, the liquid flowing through the interior of the valve so that the pressure of the water does not tend to jam 95 the valve against its seat. Also that the float may adjust the valve automatically either directly or through intermediate mechanism. Also that the whole device is detachable so that the valve is practically a 100

knockdown construction and thus may be readily packed and shipped, and also may be cleaned so as to be sanitary.

It will be understood that changes and modifications may be made without departing from the spirit of the invention.

What I claim is:

1. A device of the class specified having a tubular valve chamber, a side inlet passage to said chamber, a tubular valve having a tubular extension projecting through one end of said chamber, an operating member extending through said extension, valve and valve chamber, and means for permitting adjustment between said operating member and said extension.

2. A device of the class specified having a vertical valve chamber provided with a side inlet, a valve in said chamber of sufficient length to normally close said inlet and operable by a float to control said inlet in accordance with the position of said float and a valve stem extending upwardly from said valve and guided by the top of the valve chamber.

3. A device of the class specified having a vertical valve chamber provided with a side inlet and a bottom outlet, a hollow valve in said chamber, said valve being adapted to normally close said inlet and to open said inlet when actuated downwardly by a float, whereby to permit flow from said inlet over the top of said valve and out through said outlet, a valve stem extending upwardly from said valve and guiding means for said valve stem.

4. A device of the class specified having a valve chamber, a side inlet and a bottom outlet therein, a hollow valve normally closing said inlet, a float, and an operating rod, said rod projecting through said valve and outlet and connecting the top of said valve to said float whereby the flow from said inlet over the top of and through said valve and out said outlet is controlled by the position of said float.

5. A device of the class specified having a valve chamber, a side inlet and a bottom outlet therein, a shoulder in said chamber above said inlet, a hollow slideable valve, an extension thereon, an operating rod extending through said extension, said valve and said outlet and operable by a float, whereby said valve normally closes said inlet and engages said shoulder and is adapted to create a substantial opening of said inlet for a small movement of said valve.

6. A device of the class specified comprising a valve chamber having an open bottom forming an outlet, a side inlet, an abutment, a tubular valve having an upper hollow extension projecting through the top of said chamber, an operating rod and a float, said rod being secured to the interior of said extension and projecting through said valve

and outlet and operable by said float to actuate said valve to open and close said inlet in accordance with the position of said float.

7. A device of the class specified comprising a valve chamber, a bottom outlet, a side inlet, a float controlled valve operable in said chamber and through said outlet and adapted to fall and permit flow from said inlet through said valve and outlet upon lowering of said float, and to be raised and prevent said flow when said float is elevated, a removable top for the valve chamber and a valve stem extending up through said top.

8. A device of the class specified comprising a vertically arranged tubular casing providing a valve chamber, a tubular valve working in said casing, said casing having a side opening forming an inlet and said valve being arranged to open and close said inlet, said valve being arranged for movement opposite and below the inlet so as to permit fluid to flow into the inlet and over the top of the valve and thence downwardly through the same when the valve is lowered, a tubular valve stem extending upwardly from the top of the valve and through an opening in the top of the valve casing so as to project above said top, a float arranged below the valve casing and having a rod extending upwardly through the valve casing and valve and into the tubular valve stem, and means for adjustably connecting the valve stem and float rod, said means being located above the top of the valve casing and therefore accessible when the device is assembled.

9. A device of the class specified comprising a tubular valve casing forming a valve chamber and having a side inlet, a tubular valve located in said casing and controlling said side inlet, a tubular valve stem extending up through the top of the valve casing and projecting beyond said top, and a device for operating said valve, said device having a rod or stem extending up through the tubular valve stem and means for adjustably securing said rod and valve stem together, said means being arranged above the top of the valve casing.

10. A device of the class specified comprising a tubular valve casing having a side inlet, a tubular valve arranged in said casing and controlling said inlet, a removable top for said valve casing, a tubular valve stem extending up from the top of the valve and through the removable top of the valve casing, an operating member for actuating said valve, said member having a rod extending through the valve and into the tubular valve stem, and means above the top of the valve casing for detachably connecting said valve stem and said rod together.

11. A device of the class specified comprising a vertically arranged valve casing having a side inlet opening and an open bottom forming an outlet opening, a removable top for

5 said valve casing having means for holding
said top detachably in position, a tubular
valve in said casing, a tubular valve stem
extending up from the valve through
said removable top, a float arranged
below the valve casing and having a rod ex-
tending up through the valve and stem and
through the removable top of the valve cas-
ing, and means for detachably and adjustably
10 connecting the valve stem and float rod to-
gether above the valve casing top.

12. A device of the class specified comprising
a valve chamber having a side opening, a
shoulder just above said opening, and an open
15 bottom, a sleeve valve cooperating with said
shoulder and thereby limited in its movement
to its position for closing said opening
and having its length substantially that of
the side opening so that a small movement of
20 the valve will create a comparatively large
inlet opening, and operating means for said
valve extending through said open bottom.

13. A device of the class specified having a
vertical valve chamber provided with a side
25 inlet, a tubular valve in said chamber having
its length substantially that of said inlet, and
a float to open and close said inlet in accord-
ance with its position connected to said valve
by a small rod.

30 In witness whereof, I hereunto subscribe
my name this 12th day of December, A. D.
1924.

CHARLES B. MACK.
